UNITED STATES PATENT OFFICE.

CHARLES C. KRIEBLE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

KNITTING MACHINE.

Application filed September 19, 1922. Serial No. 589,094.

To all whom it may concern:

Be it known that I, CHARLES C. KRIEBLE, a citizen of the United States, and a resident of Norristown, in the county of Montgomery and State of Pennsylvania, have invented certain new and useful Improvements in Knitting Machines, of which the following is a specification.

The invention is designed particularly for 10 making neckties, but is not limited to such use.

The invention consists in the features and combination and arrangement of parts hereinafter described and particularly pointed 15 out in the claims.

In the accompanying drawings:

Fig. 1 is a front view of a knitting machine embodying the invention.

Fig. 2 is a side elevation.

20 Fig. 2^a shows details.

Fig. 3 is a plan view.

Fig. 4 is a detail plan view.

Fig. 4^a is a detail.

25 Fig. 5 is a developed view of the sets of needle cams and trick wheels, showing also diagrammatically the needle wave and the yarn feed ends.

Fig. 6 shows the device for lowering the 30 stitch cam.

Fig. 7 shows the star wheel and ratchet used for various purposes.

Fig. 8 is a view of the stitch cam post.

Fig. 9 is a view of the needle raising cam post.

35 Figs. 10, 10^a, 11, and 12 are views of power transmitting slides.

Fig. 13 is a view of a portion of the jacquard paper strip.

Fig. 14 is a detail view.

40 Figs. 15, 16, 17 and 18 are views of details relating to the selector devices.

Fig. 19 is a plan view of the gear for driving the needle cylinder and certain cams mounted thereon.

45 Fig. 20 is a sectional view of the needle cylinder and the gear for driving the same.

Figs. 21 and 22 are views on a reduced scale of a bracket for supporting and guiding certain parts.

50 Figs. 23 and 24 are views of guide means for the yarn feed fingers and the yarns.

Figs. 25 and 26 are views of pull and push pawls.

Fig. 27 is a view of a detail.

Fig. 28 is a section of the needle cylinder, 55 and sinker dial and cam.

Fig. 29 is a bottom plan of the sinker cam.

The machine has a revolving needle carrier 1, the needles being indicated at 2.

There is a group of main yarn guide 60 fingers at each side of the machine, these being for different colors or kinds of yarn. The fingers 3 of each group are pivotally mounted side by side at 4 in brackets 5 fixed to the sinker cam ring 6 which is held 65 against rotation by a stud 7 extending from a bracket 8, said stud entering a notch in the cam ring.

The main yarn fingers 3 incline downwardly and inwardly from their pivots towards the axis of the machine and feed the 70 yarn to the needles through mouths 10, 10' of a latch guard ring 11 fixed by screws 12 to the stationary top plate or sinker cam ring of the machine. These fingers are 75 thrown down into operative position by vertical push rods 13 mounted to slide in the brackets 5. These push rods are operated selectively by a plunger 14 which is positioned under the proper push rod by the movement of a carrier block 15 which is slidably mounted in the bracket 5. The plunger, therefore, may be defined as a member for operating the yarn fingers, and it is mounted on the carrier. The lower end of the 80 plunger rests upon a lifter plate 16 which is of sufficient width to insure contact with the lower end of the plunger in all positions to which the latter may be moved by the carrier according to the demands of the 85 pattern mechanism, as will be described hereinafter. This lifter plate is pivoted at 17 to the fixed bracket and it has a roller 18 designed to be acted on by a rotary cam member 19 fixed beneath the rotary sinker 90 bed. This cam operates the lifter and if the plunger 14 has been moved by its carrier 15 to a position under one of the push rods 13 (there being four in each group) the rise of the outer end of the lifter will elevate the 100 plunger and cause it to push up on the proper rod 13, which, acting on the tail 3' of the yarn finger will throw this down to feeding position. The cam 19 has an incline 19' which gives to the roller 18 its 105 downward movement sufficient to lower the yarn finger, as just stated, to feeding position. It has an additional rise 19'' which

gives the yarn finger a slight additional downward movement, the result of which is that a projection 3" of the depressed finger will throw down a latch plate 20, and as soon as the finger has reached its final position the latch plate will rise under the action of its spring 20' and said operated yarn finger will be retained in its operated position to continue feeding the yarn. The same action, just described, which results in the depression of the latch plate by the movement of the operated yarn finger downward to feeding position will release any one of the yarn fingers of this group so that this will rise and withdraw its yarn from work. This rise of the released yarn finger will be due to the action of the spring 3^a with which each yarn finger is provided at its pivot. Fig. 1 shows one finger in low or feeding position held by the latch plate and the upper or released position of one of the fingers is also shown. The release of a finger from feeding position, above mentioned, is due to the fact that when the new yarn finger is thrown down, its projection engages and presses down the outer end of the latch plate by working against the upper surface of its upstanding latch portion and carries this low enough to release the projection 3" of the finger which has been feeding. Any push rod 13 which may be operated can fall down to normal position as soon as the plunger 14 moves away from its lower end, and in this lowered position the push rods rest upon the upper surface of the plunger's carrier block 15. The plunger itself is under tension of a spring 14' (seated between the walls of the carrier, which is channel shaped) which forces it downward. In its upper position the plunger will be retained by a detent 14" which is in the form of a leaf spring 14^x having the detent projection 14" to enter a notch 14^a in the plunger, i. e., the same notch which the end of spring 14' lies in, but this happens only when the carrier 15 is at the left hand limit of its stroke, which is its normal position. The holding up of this plunger also has the effect of keeping the lifter plate 16 up, so that its roller, which is biased by gravity to be normally down, will not be hit by the rotary cam 19, and therefore the lifter plate will not flap up and down idly. This condition is illustrated on the right of Fig. 1. When, however, the plunger carrier 15 is moved to the right, Fig. 2, from its normal position of rest at the left of the group of push rods, the plunger will move away from and will no longer be retained by the detent, and hence the spring of the plunger will force it down and thus tip the lifter plate into position, so that its roller will be within the range of the cam 19 and hence will be operated by said cam to swing the outer end of the plate upwardly and thus raise the

plunger to move the proper yarn finger into feeding position and release the other finger, so that it may rise to inoperative position under the action of its spring. This downward movement of the plunger when the carrier moves to the right is due also to its working against an incline 14^b on the frame or bracket.

The plunger carrier is moved towards the right, from its left hand position shown in Fig. 2, by pattern mechanism as follows:

A rod 21 connects the sliding carrier with a lever 22, fixed to a shaft 23 mounted in the fixed bracket 8 supported on the fixed base 24 of the machine. The shaft 23 is operated by an arm 23' whose hub is pinned thereto at 23", the depending end of which arm engages a notch 25' in a slide 25, Figs. 3 and 12, which has pivoted at 26 four pull bars 27, Fig. 3, each of which rests upon one of the pins 28 mounted in a carrier bar 29, so as to slide freely therein, in a substantially vertical direction. This carrier bar has movement up and down in relation to the perforated pattern strip or jacquard device 30 which in the present case consists of an endless sheet of flexible material, as paper 30', passing over a pattern drum 30 referred to more fully hereinafter. The up and down movement of the pin carrying bar is derived from a cam 31 arranged coaxially with the needle cylinder and adapted to operate against a roller 32 carried by a slide 33 which is guided in the bracket 34, Figs. 2 and 4. This slide bears against an eccentric pin 35' carried by a rocking arm 35 which is pivotally mounted at 36 and is connected with an arm 37 which has thereon the pin carrying bar 29. A spring 38 presses the arm down and the cam 31 through the connections described raises the pin carrying bar. When the pin carrying bar is raised it engages the heads of the pins and holds them up. The jacquard strip is perforated and is moved step by step by the intermittent movement of the drum 30 which has teeth 30' engaging marginal openings in the strip. Now when the pin carrying bar moves down, any pin which finds an opening in the paper strip will pass therethrough, but any pin which strikes an imperforate part of the strip will be held up despite the fact, as just stated, that the pin carrying bar has lowered. The pin which passes through the perforation in the paper strip will of course move down and this will allow the pull bar 27, which is resting thereon, to fall also, and this will bring a shoulder 27' on the pull bar into range of an oscillating push plate or bar 39 with the result that, supposing the push plate is moving towards the left in Fig. 2, the pull bar 27 which has fallen will be pushed leftward and drawing upon the slide 25 will operate the arm 23' which engages its notch 25', Fig. 3, and turn the

shaft 23, thus swinging the arm 22 towards the right and moving the plunger carrier 15 rightward to bring the plunger 14 under the proper push bar 13 for operating the 5 corresponding yarn feed finger into operative position, when the lifter plate 16 moves upwardly. The train of connections just described will be returned to normal position, as will be hereinafter described. The 10 pull bar which has been operated, as just described, will be elevated to normal position by the rise of the pin carrying bar 29 which will elevate the pin upon which said pull bar rests, and when raised to this normal 15 position the said pull bar will be out of range of movement of the oscillating bar 39, ready for another action such as just described, when the pattern strip calls for it. As before stated, there are four pull 20 bars 27 connected with the one slide 25, and the shoulders 27' of these pull bars are in line with each other, see Fig. 3, but it will be noticed that the oscillating bar 39 has a series of shoulders 39' in stepped relation, 25 and consequently at different distances from the shoulders 27' of the pull bars 27, so that the slide 25 will be moved different distances, according to which one of the 30 four pull bars is lowered into range of the oscillating bar 39. The bar 39 oscillates always through the same length of arc, it being mounted on a frame 39'' pivoted at 39^x to the bracket 34, Fig. 2, and it is operated as will be described hereinafter. If the 35 first one of the pull bars 27 (counting from the bottom of Fig. 3) is the one lowered, then the oscillating bar 39 will move this the maximum distance, because its shoulder 27' stands nearest to the edge of the bar 39. 40 This pull bar will therefore cause a full rightward movement of the plunger carrier 15 and the plunger 14 will select the right hand push bar 13 to throw the right hand yarn finger down to operative position. If 45 the second pull bar 27 is lowered, there will be some lost motion of the oscillating bar 34 so that the plunger carrier 15 will not be moved so far to the right as in the first instance, and consequently the 50 plunger 14 will select and operate the second yarn finger (counting from the right of the group A, Fig. 3) and so on as to the other pull bars 27, each in order being operated to a lesser degree than the preceding 55 one, owing to the stepped formation 39' in relation to the shoulders 27' of the pull bars. The train of mechanism just described has relation to the group of yarn fingers A. A similar operation takes place in relation 60 to the group of yarn fingers indicated at B, Fig. 3. There is a plunger carrier 15^a for this side of the machine with a rod 21^a, a lever 22^a, and a shaft 23^a, which latter is arranged axially in line with the shaft section 23^a above mentioned, and this shaft section 23^a

is operated through an arm 23^b fixed thereon from a slide 25^a which is like the slide 25 and has four pull bars 27^a pivoted thereto, to be controlled by certain of the pins 28 and operated severally by the same oscillating bar 39 when the pins find openings in the 70 jacquard strip through which to pass when the carrier bar 29 is lowered.

It will be noted that the fingers of group A may be selected in any prescribed order 75 desired, the variations in the order of selection depending upon the disposition of the holes in the jacquard strip, and this is true also of the group of fingers B and the order of selection of one group may be entirely 80 different from that of the other group. In other words, the two groups are entirely independent of each other in the sense that the order of selection of the fingers of one group may vary indefinitely in respect to 85 the other group, though the selection in respect to the two groups is derived from the same source, i. e., the jacquard strip.

The push plate 39 is operated by a spring 40 in one direction, this spring being connected to the swinging frame 39'', and in the other direction the operation is due to a cam 41 operating against a roll 42 mounted on a slide 33' which bears against an adjusting screw 43 carried by the frame. The eccentric pin 35' of the lever 35 may be turned for adjustment of its contacting relation with the slide 33 by a screw driver, the head of this pin being kerfed, and when adjusted it is held by a set screw 35''. The 90 rocking of the frame 39'' is utilized for operating the pattern drum step by step, for which purpose the frame carries a pawl 44 to engage the teeth 45 of the drum. This pattern drum is substantially like that shown 95 in an application of Howie and Taylor, Serial No. 549,253, filed April 3rd, 1922. It involves a rotary part 30 which has the teeth which drive the pattern strip and a stationary part 30^a which is fixed to the bracket 100 arm 30^b at 30^c and this stationary part has the opening or openings 30^d through which the pins 28 pass when an opening in the jacquard strip aligns therewith and when the pin is lowered by the bar 29. 115

In order to return the carrier slide 15 to normal position at the left of Fig. 2 after being operated to the right (it being observed that the pull bars 27 have only the advancing shoulder 27' but not the return shoulder, see Fig. 3) the lever 22 has a downward extension 22^x connected by a rod 46 with an arm 47 on a vertical shaft 48 mounted in the fixed base of the machine and in a bearing 49, Fig. 1, and this shaft carries an arm 50 fixed thereto which is in the path of a roller 51 on the shaft 52 forming a part of the rotary take-up mechanism. This mechanism may be of any suitable type and needs no detail description herein, except 125 130

to say that revolving frame of this take-up mechanism is shown at 53, and this affords bearings for the shaft 52, one of which is indicated at 54. The shaft is 5 driven by a gear 55 meshing with a circular rack 56 which is supported in fixed relation to the frame by arms 57. The shaft 52 carries the clutch 58 which drives the take-up rolls located within the fabric cam 59 10 and not shown, these rolls being journaled in the revolving take-up frame 53. The roll 51 travelling about the axis of the machine will hit the arm 50 and through the rock shaft 48 and the connections just described 15 the lever 22 will be returned to the normal position shown in Fig. 2, with the selector plunger 14 at the left of the series of push rods 18 and with the pull bars 27 restored to normal position.

20

Needle cams.

The machine being a two feed type, there are two sets of needle cams, shown in Fig. 5, consisting of stitch cams *a*, *a'*, raising cams 25 *b*, *b'*, and fixed cam pieces *c*, *c'*, and *d*, *d'*, and there are two trick wheels *e*, *e'*, at diametrically opposite sides of the machine.

Each of the stitch cams is adjustable automatically to knit tight or slack and for this 30 purpose each is screwed to a post 59 which is normally pressed upwardly by a spring 59' pressing against a lateral projection 59'' of the post, the spring being seated in a pocket of the cam block, as in ordinary practice. For automatically lowering the stitch cam against the pressure of this spring, the post is notched at 59* and a crank member or pin 60 enters this notch. This crank pin is journaled in the cam block and on its 35 outer end it has fixed thereto an arm 60' carrying a screw pin 60'' to bear on a controller ring 61, Fig. 1, which on its edge is formed with ratchet teeth 61' and on its upper surface is formed with high and low 40 surfaces 61^a and 61^b. The controller ring is moved step by step by a pawl 62 pivoted to a lever 63, Fig. 3, which is pivoted at 64 to the base of the machine and is operated by a slide 65, guided in the frame of the 45 machine and having connected pivotally thereto at 66 a pull bar 67, which, like the pull bars before described, is operated leftward, Fig. 3, by the push plate 39. This pull bar has two shoulders, like the one which appears in Fig. 2, so that the push plate 39 50 will engage one shoulder to advance the pull bar leftward to turn the controller ring in the arrow *y* direction, Fig. 3, and when the push plate 39 returns to the right it will 55 engage the other shoulder of the pull bar and return it to normal position to retract the pawl for a fresh operation. No detent is required to hold the controller ring against overthrow, as the action is not rapid and 60 the friction is sufficient to prevent undue

movement. One step movement will cause a high part of this controller ring 61 to tip the arm 60' up and this, as indicated at the right of Fig. 5, will cause the flat face of the pin 60 to engage the lower shoulder of 70 the cam post 59 and lower the stitch cam for making slack stitches, and when the next step movement of the controller ring takes place, according to the demands of the pattern mechanism, the low part 61^b of the controller ring will allow the arm 60' to lower, thus turning the crank pin, so that the spring 59' then becomes effective to raise the cam post 59 and allow the stitch cam to assume 75 position for knitting normally tight. 80

The control just described is exerted at both feeds simultaneously, because the turning of the controller ring will operate the two stitch cams *a* and *a'* simultaneously, it being understood that there is a crank pin 85 60 and arm 60' at each of the stitch cams. The knitting of the slack course is for making, for instance, the neck band portion of the necktie.

The needle raising cams *b*, *b'* are pressed 90 normally downward by springs 68 and they are raised by star wheels or cams 69 which lie in the notches 69' of their posts 69'', the springs being pocketed in the posts and held in place by overlying plates 69* fixed 95 to the cam box. The star cams are formed in one piece with the hubs 70 of ratchet wheels 70' which are turned step by step, and at such intervals as are prescribed by the pattern mechanism by pawls 70''. 100

The hubs 70 are journaled in the cam housing or box 71. The pawls 70'' are reciprocated once for each revolution of the machine. They are pivotally connected with rocking arms 70* mounted on a shaft 70^a, 105 Fig. 2. The arm 70* is rocked by a rod 72, Figs. 2 and 3, connected with a bell crank 72' pivoted to the base of the machine and operated by a slide 72'' having a pin 72* engaging a notch in the bell crank lever. 110 The slide moves in a guide-way in the base of the machine and at its inner end it has a roller 73, dotted lines Figs. 1 and 3, adapted to be struck by cams 73', 73'', the former of which moves the slide radially inward, and the latter of which moves the slide radially outward. These cams are carried by the bevel gear 74, dotted lines Fig. 1, which transmits rotary motion to the needle cylinder, it being driven by the bevel gear 74' on 115 the main drive shaft 74'', Fig. 1. 120

Not every stroke of the pawls 70'' is effective in turning the ratchet wheels 70', but only when the pattern mechanism calls for it. For controlling these pawls star cams 75 are provided, one of which is shown in Fig. 2, and both of which are shown in Fig. 3. These star cams are connected or formed with ratchet wheels 75', these being mounted 125 to turn freely about the shaft sections 23, 130

23^a. The pawls 70" simply rest on the star wheels and when these are turned to present their high points beneath the pawls the latter will be lifted so as to miss their ratchets 5 70' and hence no change in the position of the needle raising cams b, b' will take place, whereas when the ratchet wheels 75' are given their next step movement the flat or low sides of the star cams will come under 10 the pawl bars 70" and these will lower so as to engage and turn the ratchet wheels 70' on their next stroke to the right, thus to adjust the needle raising cams b, b' vertically.

15 The ratchet wheels 75' are turned step by step by pawls 75^x pivotally mounted at 75^a to slides 76, one for each side of the machine, Fig. 3, each of which has a pull bar 76' resting on one of the pins 28 to be controlled 20 thereby as to its up or down position in respect to the push plate 59 which is to operate them in a manner before described.

Each of these pull bars is advanced and retracted by the push plate 39.

25 The vertical adjustment of the needle raising cams cooperates with trick wheels in forming the pattern. If these cams are in their lower positions those needles which are not raised to clear their latches will pass 30 these cams in tucking position and tuck stitches will be formed on these needles, while those needles whose butts engage the seats in the trick wheel will knit, whereas if these raising cams are in their elevated 35 positions all needles will knit, because those which pass by the trick wheels in tucking position will be raised by the cams b, b' to clear their latches and hence these needles also will knit.

40 *Auxiliary yarn fingers.*

Supplemental yarn feed fingers are shown at f and g. These are pivotally mounted in a bracket 77 and are raised and lowered by 45 push rods 77' and springs, as at 77''. The push rods are operated by star cams at 78, Fig. 2, turned by ratchet wheels 78'. Pawls 78" turn the ratchet wheels and these pawls are worked by levers 79 loosely mounted on 50 the shaft 23 and operated by slides 79', 79'', which are operated by the pull bars 80, 80', of the pattern mechanism. These fingers are adapted to feed only those needles which are raised to knitting position by the trick 55 wheels. They will not feed those needles which leave the trick wheel in tucking position and hence variations in the pattern can be produced by throwing these fingers into and out of work. These auxiliary fingers, 60 when lowered to feeding position lie just below the elevated throat 10" of the ring 11, see diagram Fig. 5, so that they feed the yarn over the edge of this throat to the needles which are fully elevated by the trick 65 wheel. This feeding position of the auxil-

iary yarn finger is indicated at f, Fig. 5, and its raised position at f'. The raised position of the other auxiliary yarn finger is indicated at g. Its feeding position is at the same low level of the finger at f. This difference in the elevated positions of these two fingers is for the purpose of preventing the two yarns from winding or twisting together clear up to the yarn fingers from the center of the fabric, which, if it happened, would prevent the yarns from being fed to the needles properly when the auxiliary is lowered to feeding position. In other words, by giving a separated position to the two auxiliary yarn fingers when raised equal 70 to the distance between f' and g, the two auxiliary yarns are kept apart, so that each may be lowered to feeding position individually without interference by the other 75 yarn. The feeding position of the main 80 yarn fingers is indicated at A' and their elevated positions at A. They lie when lowered to feeding position in the throat space 10. The height of the needle wave resulting from the trick wheel seats e' lifting certain of the needles is indicated at e² 85 and the low wave line at this point due to the needle butts passing through the cuts e'' in the trick wheel periphery is indicated at e^x. The wave line passing the main 90 yarn fingers may be low, as indicated at b'', if cam b' is down, or it may be higher up, if cam b' is raised, but in either case the yarn 95 will be taken by all of the needles at this point. The feed mouth for the other group 100 of yarn fingers B is shown at 10'. A guide finger o projects up from the throat 10" to properly control the yarn fed over the edge of the throat.

The main yarn fingers when lowered to 105 feeding position direct the yarn between or alongside of guards p, three in number, and consisting of thin plates depending from a bar p' extending across and secured to the top of the ring 11. These plates have their 110 lower edges inclining downwardly and inwardly towards the center of the machine and direct the idle yarns from the fingers which are raised towards the machine's axis, where these idle yarns are twisted into a 115 rope or cord form. This action is also assisted by a guard p² consisting of a wire attached to bar p' and inclining downwardly and inwardly. When a yarn finger 120 is raised, the point where this yarn is tied into the fabric of course travels with the needle row and this idle yarn, by coming against the inclined edges of the guards p and p², which in effect present a depending cone formation with apex downward, will 125 be directed downwardly and to the axial center of the machine, where they will be twisted together, but by the use of the guards the yarns will be kept separate for 130 a considerable length thereof extending 130

from the yarn fingers, and thus each may be lowered individually without interference by the other yarns, it being observed that the point where the twisting begins is 5 below the level of the feeding positions of the yarn fingers. Suppose in Fig. 3 that one of the yarn feed fingers is lifted out of work. The yarn end which is tied into the fabric will travel in the arrow direction and 10 extend across the interior of the needle cylinder, but it will be depressed at its center by sliding down the inclines of the plates p and bar p^2 , and as the rotary movement continues and additional idle yarn is drawn 15 off, it will twist together at the center of the cylinder.

I provide means for counting the number of neckties knit. This consists of counting mechanism C, Fig. 2, operated by a rod 81, 20 Fig. 2, from a lever 82, the lower arm of which is operated by a slide 83, Fig. 3, having a pull bar 84 controlled by the pattern mechanism before described.

Reverting to the yarn finger selecting 25 mechanism and particularly to the action of the plunger 14 and the return arm 50, it will be observed that this return arm, when struck by the roller 51, will return the plunger carrier 15 towards the left, Fig. 2, 30 until the plunger 14 gets under the cam incline 14^b of the bracket. Further movement of the plunger carrier leftward will be due to the rise of the plunger under the action of the lifter plate 16, which will force 35 the plunger up into contact with the said cam incline 14^b and thus shift it further leftward. This will have the effect of throwing the return arm 50 further out, so that it will be entirely outside the path of 40 movement of the roller 51, so as not to be hit idly thereby. This action just described will set the parts at the pattern mechanism in normal position so that at the proper time the plunger carrier will be moved 45 towards the right, the plunger 14 will be lowered, together with the outer end of the lifting plate 16, so that its roller 18 will now be in the path of cam 19, and the return arm 50 will be set inward to be struck by 50 the roller 51 when this comes around to restore the mechanism partway to normal position, this taking place after the lifting plate 16 has operated to raise the plunger 55 14 and change the yarn fingers.

55 The machine is provided with so-called sinkers or web holders of substantially known form and operation.

In Fig. 5 only a few of the notches of the trick wheel are shown, this being for convenience of illustration.

Certain features disclosed herein have been made the subject of and claimed in divisional applications for knitting machines filed May 2, 1924, Serial No. 710,627, 60 and knitting machines filed July 18, 1924,

Serial No. 726,793, the former relating generally to the needle cam organization and mechanism for changing the positions of said cams and the latter relating to pattern mechanism.

70

I claim—

1. In a knitting machine and in combination, a set of yarn feed fingers free from interconnecting power transmitting means between them, pattern means for throwing said fingers individually to feeding position, and means for automatically throwing the finger which has been feeding out of action as a consequence of the movement of a finger to feeding position said means being controlled by the latter finger.

75

2. In a knitting machine and in combination, a plurality of yarn feed fingers, pattern means for selecting and throwing the fingers individually to feeding position, detent 85 means for holding the fingers in feeding position arranged to engage a portion of the feeding finger, said detent means releasing the feeding finger for its return to non-feeding position when another finger is moved to feeding position, and means for returning the finger to normal position when released by detent means, substantially as described.

80

3. In a knitting machine and in combination, a set of yarn feed fingers, pattern means for throwing the fingers individually to feeding position, detent means for holding the fingers to feeding position, said detent means releasing the feeding finger for its return to non-feeding position when another finger is moved to feeding position, said detent being operated to release the finger which has been feeding by contact of 90 a portion of said other finger as it moves to feeding position.

95

4. In combination, a group of yarn feed fingers arranged side by side and pivotally mounted, means for moving the fingers to feeding position, a detent engaging the fingers near their free ends, said detent being operated to release position by contact of either of the fingers on its way to feeding position to thereby free the finger which has been feeding, so that it may return to non-feeding position, said detent then engaging the finger which has just operated it to hold it in feeding position, substantially as described.

100

5. In combination in a knitting machine, a group of yarn feed fingers, a detent engaged by a portion of any one of the fingers on its way to feeding position to thereby release the finger which has been feeding, said detent thereafter engaging the newly positioned finger to hold it in feeding position.

105

6. In combination in a knitting machine, a group of yarn feed fingers, pivotally mounted side by side, a detent plate, each of said fingers having a portion to engage said plate and release it from the finger which

110

115

120

125

130

has been feeding before the finger which is nearing feeding position reaches said position, said detent then assuming position to hold the newly operated finger in its feeding 5 position, substantially as described.

7. In combination, a group of yarn feeding fingers pivoted side by side at their upper ends, means for throwing the fingers down to feeding position, a detent plate adjacent the feeding point to be engaged and depressed by the feed fingers just before they reach feeding position, to thereby release the finger which has been feeding, a spring for raising each feed finger when released by the detent, and a spring for raising the detent from its depressed position to engage and retain the finger which has just operated it in moving to feeding position, substantially as described.

10 8. In combination, a group of yarn feed fingers movably mounted to be thrown to and from feeding position, a plunger with means for shifting it to different positions to select the desired yarn feed finger to be thrown to feeding position, and detent means for holding the fingers when thrown to feeding position and for releasing the finger which has been feeding for its return to non-feeding position, said releasing being effected by the contact of the newly selected finger with said detent means, substantially as described.

15 9. In combination, a group of yarn feed fingers pivotally supported, detent means on one side of the pivot for holding the fingers in feeding position and adapted to be struck and operated by another finger to release the one that has been feeding as said other finger is moved to feeding position to be held by said detent, each of said fingers having a tail portion on the other side of said pivot, and means for selecting and operating the yarn fingers by contact with said tail portions, substantially as described.

20 10. In combination, a group of yarn feed fingers pivotally mounted, push bars arranged side by side for operating the fingers, a plunger for selecting and operating the push bars, a movable carrier for the plunger with means for shifting it to different selective positions, and means for operating the plunger when set in any one of its selecting positions, substantially as described.

25 11. In combination, a group of yarn feed fingers pivoted side by side, a carrier movable in a plane parallel with the pivot axis of the fingers, a plunger on the carrier, means for moving the carrier to different positions so that the plunger will select and operate the desired yarn feed finger, and means for operating the plunger in any one of its selective positions, substantially as described.

30 12. In combination, a group of yarn feed fingers pivotally mounted side by side and

having tail portions, a carrier with means for reciprocating it transverse to the planes in which the fingers swing, a plunger on the carrier, means for operating the plunger substantially vertically, and push rods movable substantially vertically when operated by the plunger, said rods engaging the tails of the fingers to throw them into feeding position, substantially as described. 70

13. In combination in a knitting machine, a rotary needle carrier, yarn feed fingers, a reciprocating carrier, a plunger thereon for selecting the yarn feed fingers according to the pattern desired to be thrown into and out of feeding position, means for operating the selecting plunger to operate the yarn feed fingers and a cam rotating coaxial with and on the needle cylinder for actuating the latter means. 75

14. In combination in a circular knitting machine having a rotary needle cylinder, a plurality of independently operable yarn feed fingers arranged side by side, a selecting device movable back and forth along the group of yarn feed fingers, pattern mechanism for giving said selecting device its movement for setting it to operate the yarn feed fingers in prescribed order, and means rotating about the vertical axis of the machine with the needle carrier for actuating the selecting device to move the selected yarn feed finger to its feeding position, substantially as described. 80

15. In combination a knitting head, a group of yarn feed fingers pivotally mounted in a vertical plane, a carrier having back and forth movement beneath the lower ends of the push rods, a plunger on the carrier, a cam on the knitting head, and a member moved by said cam in a vertical plane for operating said plunger, substantially as described. 100

16. In combination a needle cylinder, a group of yarn feed fingers, a member shiftable to different positions in respect to the group of yarn feed fingers for selecting the yarn fingers in desired order, pattern mechanism for shifting said member, and means for operating the member in any of the positions to which it is shifted for operating the selected yarn finger, said means consisting of a plate having to and fro movement and a cam member rotating with the needle cylinder for operating said plate. 110

17. In combination, a group of pivotally mounted yarn fingers, a carrier reciprocating in a plane parallel with the pivot axis of said fingers, a member on the said carrier common to all the fingers, means for shifting the carrier to different degrees and into positions to make the said member align with and select the desired yarn feed finger, a pivotally mounted plate swinging in a 125

130

- vertical plane, and a cam rotating with and about the axis of the knitting head for operating the said plate, substantially as described.
- 5 18. In combination in a circular knitting machine, groups of yarn feeding fingers located at substantially opposite sides of the knitting head and pivotally mounted, a pair of slidable carriers, one for each group of 70
10 yarn feed fingers, pattern mechanism for shifting said carriers transverse to the planes of movement of the yarn finger, a member on each carrier for selecting and operating the yarn feed fingers in the prescribed order according to the pattern called for, and means for operating the said member while in any one of the several positions to which it is shifted by its carrier, substantially as described.
- 15 19. In combination, a group of yarn feed fingers pivotally mounted, a carrier reciprocable in a plane parallel with the axis of the pivots, a member on the carrier for operating the fingers individually according to 80
20 the positions to which the carrier is shifted, means for operating said member, a pull bar connected with the reciprocating carrier and reciprocable in the same direction therewith, and means controlling the times of operation 85
25 of the pull bar, substantially as described.
- 20 20. In combination, a group of yarn fingers arranged side by side, a carrier having a back and forth movement transverse to the plane of movement of the yarn fingers, a member on the carrier to operate the yarn fingers, a rod connected with the carrier, a lever connected to the rod, a rock shaft carrying the lever, a slide for turning the rock shaft, said slide being movable parallel with 90
30 the carrier, a pull rod connected with the slide pivotally, a pattern mechanism for controlling the rise and fall of the pull rod, and a member to engage and operate the pull rod when it is lowered, substantially as described.
- 35 21. In combination in a knitting machine, a group of yarn feed fingers, a carrier with means thereon for selecting and operating the yarn fingers according to the position to 95
40 which the carrier is shifted, a pull bar connected with the carrier for moving it in one direction, means for operating the pull bar, pattern means for determining the times of operation of the pull bar, and means for restoring the carrier to normal position, consisting of a member rotating with the machine, and connections operated thereby, substantially as described.
- 45 22. In combination in a knitting machine, a group of yarn feed fingers, a carrier with means thereon for selecting and operating the yarn fingers according to the position to which the carrier is shifted, a pull bar connected with the carrier for moving it in 100
50 one direction, means for operating the pull bar, pattern means for determining the times of operation of the pull bar, and means for restoring the carrier to normal position, consisting of a member rotating with the machine, and connections operated thereby, substantially as described.
- 55 23. In combination in a knitting machine, a group of yarn feed fingers, a reciprocating carrier having a member thereon for operating the yarn feed fingers individually, a pull bar connected to the carrier for moving it in one direction, pattern means for moving said pull bar up and down, a reciprocating member for engaging and operating the pull bar when in its lowered position, means for operating the reciprocating member including a cam rotating with and about the axis of the needle cylinder, means for returning the carrier to normal position 105
60 consisting of a member travelling about the axis of the needle cylinder and connections operated by said member, substantially as described.
- 65 24. In combination, a group of yarn fingers, a reciprocating carrier member, a plunger carried thereby to select and operate the yarn feed fingers individually according to the position to which the carrier is moved, a fixed frame having a cam incline against 110
70 which the plunger bears when the carrier is moved from normal position to be thereby forced downwardly, a member having up and down movement and operating upon the plunger in various positions thereof, and means for operating said member to operate the plunger, substantially as described.
- 75 25. In combination, a group of movable yarn feed fingers, a carrier, a plunger on the 115
80 carrier to select and operate any one of the fingers according to the position to which the carrier is moved, means for raising the plunger for operating the yarn feed finger with which it registers and also to raise the plunger when the carrier with the plunger is in idle position, and a detent for holding the plunger elevated so that its operating mechanism will be idle, substantially as described.
- 85 26. In combination, a group of yarn feed fingers, a plunger for operating these severally, a spring for forcing the plunger downwardly, a pivoted member for moving the plunger upwardly to operate the yarn feed finger with which it registers, a cam for operating the pivoted member, said member being set in the path of the cam by said spring operating upon it through the plunger, and a detent for holding the plunger up when it is in idle position, out of line with the fingers so that the pivoted member may assume a position out of line with the cam, substantially as described.
- 90 27. In combination, a group of yarn feed 120
95 fingers, a plunger for operating these severally, a spring for forcing the plunger downwardly, a pivoted member for moving the plunger upwardly to operate the yarn feed finger with which it registers, a cam for operating the pivoted member, said member being set in the path of the cam by said spring operating upon it through the plunger, and a detent for holding the plunger up when it is in idle position, out of line with the fingers so that the pivoted member may assume a position out of line with the cam, substantially as described.
- 100 28. In combination, a group of yarn feed 125
105 fingers, a plunger for operating these severally, a spring for forcing the plunger downwardly, a pivoted member for moving the plunger upwardly to operate the yarn feed finger with which it registers, a cam for operating the pivoted member, said member being set in the path of the cam by said spring operating upon it through the plunger, and a detent for holding the plunger up when it is in idle position, out of line with the fingers so that the pivoted member may assume a position out of line with the cam, substantially as described.
- 110 29. In combination, a group of yarn feed 130
115 fingers, a plunger for operating these severally, a spring for forcing the plunger downwardly, a pivoted member for moving the plunger upwardly to operate the yarn feed finger with which it registers, a cam for operating the pivoted member, said member being set in the path of the cam by said spring operating upon it through the plunger, and a detent for holding the plunger up when it is in idle position, out of line with the fingers so that the pivoted member may assume a position out of line with the cam, substantially as described.

- 10 fingers, a plunger with means for shifting it into line with said fingers individually, a cam, means intermediate the cam and plunger for operating the latter, said means being biased to assume a position out of line with the cam, when the plunger is raised, and detent means for holding the plunger raised when not registering with any one of the yarn feed fingers, substantially as described.
- 15 28. In combination with a knitting machine, a rotary needle cylinder, a group of yarn feed fingers, selecting means for selecting the fingers in a prescribed order, including a reciprocatory carrier having a member thereon to register with the yarn feed fingers, a pull bar connected with the carrier, a push bar for operating the pull bar, pattern mechanism for locating the pull bar in 20 or out of alignment with the push bar, means operated from a rotary part of the knitting head for operating the selecting member in any one of the several positions to which it is moved by the carrier, means rotating with 25 the rotary part of the knitting head for operating the push bar, and means for returning the carrier to normal position, comprising a lever with connections operated thereby, and a member rotating with the needle cylinder for operating said lever, substantially as described.
- 30 29. In combination, a group of yarn feed fingers, a reciprocatory carrier, a plunger on the carrier which registers with the fingers severally when the carrier moves to its different positions, means having an up and down movement for operating the plunger in any of its several positions, a cam for operating said means, means for 35 returning the carrier to normal comprising a member revolving with the knitting head and an arm to be struck by said member, and a cam incline on the fixed frame to be engaged by the rising plunger for giving 40 the carrier its final restoring movement and thus removing the arm from the path of movement of said member, substantially as described.
- 45 30. In combination, a group of yarn feed fingers, pivotally mounted, a member for operating the yarn feed fingers, a carrier for said member to move it to register with the fingers severally, a plate pivotally mounted and having an arm extending from the opposite side of the pivot, a cam revolving 50 with the rotary part of the knitting head to depress said arm for elevating the plate with the plunger to throw a yarn feed finger into feeding position, and a detent on the fixed frame for engaging the plunger and holding it up when the carrier is moved to normal or idle position, said plate then assuming automatically a position with its arm out of line with the cam to remain idle, 55 and a spring for forcing the plunger down when released from its detent by the movement of the carrier from normal position, the downward movement of the plunger setting the plate in position so that its arm will be operated by the cam, substantially 70 as described.
- 60 31. In combination, in a knitting machine, a group of yarn feed fingers pivotally mounted side by side, a reciprocatory carrier, a member thereon for operating the 75 yarn feed fingers when brought into registration with the fingers severally by the movement of the carrier, means for operating said member, a lever connected with the carrier, a rock shaft on which the lever is 80 mounted, pattern mechanism for operating the rock shaft to different degrees in one direction, and means for returning the carrier to normal position comprising a pivoted arm, a member travelling with a rotary part 85 of the machine for operating said arm, and a connection from the arm to the said lever, substantially as described.
- 90 32. In combination in a multiple feed knitting machine, multiple groups of yarn feed fingers, means at each group for selecting the yarn feed fingers which are to be changed, including a reciprocatory carrier having a selecting member thereon, means for operating said selecting members, a pull 95 bar for each carrier, slides for the pull bars to which the pull bar is pivotally connected, means for operating the pull bars, and pattern means for controlling the times of engagement of the pull bars individually 100 with the operating means, substantially as described.
- 100 33. In combination in a knitting machine, yarn feed fingers, needle cams, a plurality of devices disposed and turnable about a 105 common axis for controlling the positions of the yarn feed fingers and needle cams, slides for operating said devices individually, pull bars connected movably to said slides, means for operating the pull bars, 110 and pattern mechanism for positioning the pull bars in or out of line with their operating means according to the pattern desired, substantially as described.
- 115 34. In combination in a multiple feed knitting machine, a group of yarn feed fingers at each feed, selecting means for selecting the yarn feed fingers which are to be changed, a pair of rock shafts coaxially arranged end to end, connections from the 120 rock shafts for setting the selecting means in various positions to select the desired yarn feed finger, slides having connection with the rock shafts for turning them individually, pull bars connected to the slides, needle cams, means for raising and lowering the same, devices loose on the rock shafts for controlling said means, slides having connection with said devices for 125 turning them on the rock shaft, pull bars 130

connected with the latter slides, means for operating the pull bars, and pattern means for controlling the positions of the pull bars in or out of the path of movement of their operating means, substantially as described.

35. In combination, in a knitting machine, a group of yarn feed fingers, selecting means, means for operating the selecting means in 10 the different positions to which it is set for changing the positions of the yarn feed fingers, and means for shifting the selecting means from place to place to operate the desired fingers, comprising pull bars having 15 shoulders, and a push bar having shoulders, the said shoulders being spaced apart differently to give different degrees of movement to the pull bars from a substantially uniform back and forth movement of the 20 push bar, whereby the selecting means will be moved to different degrees, and pattern means for controlling the position of the pull bars individually in or out of line with their operating means, substantially as described.

36. In combination in a knitting machine, knitting devices including yarn feed fingers and knitting cams, a group of pull bars, connections between the said pull bars and 30 the knitting devices, pattern mechanism for raising and lowering the pull bars, a pull bar operating member having a back and forth movement, some of the pull bars having two shoulders to be contacted by said 35 member for operating the pull bars back and forth, others of said bars having only one shoulder, each to be moved in one direction by said operating member, and means for restoring these latter pull bars to normal 40 position, independently of the said operating member, said last mentioned pull bars controlling the changing of the yarn feed fingers, substantially as described.

37. In combination, a group of yarn fingers, selecting and operating means therefor, means for setting the selecting means in different positions, a pair of supplemental yarn fingers, pull bars for operating said setting means and the supplemental 50 yarn fingers, and means for operating the pull bars.

38. In combination, a group of yarn fingers, selecting and operating means therefor, means for setting the selecting means

in different positions, a pair of supplemental yarn fingers, pull bars for operating said setting means and the supplemental yarn fingers, and means for operating the pull bars, said setting means including a rock shaft and means loosely mounted 60 thereon forming a connection between the supplemental yarn fingers and their pull bars, substantially as described.

39. In combination in a rotary knitting machine, a rotary head, pull bars connected with knitting devices for controlling their action, a member having a to and fro movement for operating the pull bars, a member for raising and lowering the pull bars, a jacquard strip for controlling the position of the pull bars, a cam rotating with the knitting head for operating the to and fro moving member, and a second cam revolving with the knitting head for controlling the raising and lowering member, 75 substantially as described.

40. In combination in a rotary knitting machine, a rotary knitting head, yarn feed fingers, selecting means for the yarn feed fingers, needle cams, pull bars having connection to the selecting means, a to and fro moving member for operating the pull bars, a member for raising and lowering the pull bars, pattern means controlling said raising and lowering movements, cams rotating about the vertical axis of the machine for operating the said members, a cam rotating about the axis of the knitting head with means operated thereby for operating the selecting means to change the position of the yarn fingers, cam means rotating about the axis of the knitting head with connections operated thereby for changing the position of one of the needle cams, a pull bar operated by the said member for controlling the latter connection of the needle cam, another needle operating cam, a cam ring movable about the axis of the machine with means operated thereby for adjusting the needle cam, a pull bar also operated by the said member, and a connection from said pull bar to said cam for giving it intermittent movement, substantially as described.

In testimony whereof, I affix my signature.

CHARLES C. KRIEBLE.
